KEEPER FOR THE BOLTS OF LATCHES AND
THE LIKEAlbert F. Lickteig, Grand Rapids, Mich., assignor
to Grand Rapids Brass Company, Grand
Rapids, Mich., a corporation of Michigan

Application December 20, 1937, Serial No. 180,775

6 Claims. (Cl. 292—340)

The present invention relates to keepers for the bolts of latches, adapted to be applied to refrigerators and the like; and its object is, generally, to provide such a keeper improved in respects hereinafter appearing; and more particularly, to provide such a keeper having an improved member wherewith the latch bolt operatively engages, said member being adjustable inwardly-outwardly of the refrigerator to which it is applied; and further, to provide improved means for thus adjustably mounting said member; and further, to provide improved means for securely holding said member in adjusted positions.

These and any other objects hereinafter appearing are attained by, and the invention finds preferable embodiment in, the illustrative keeper particularly described in the body of this specification and illustrated by the accompanying drawing, in which:

20 Figure 1 is an elevational front view of a latch structure comprising a latch casing and a keeper for the latch bolt, mounted respectively on the swingable closure for a refrigerator's door opening and on the jamb portion of the refrigerator;

25 Figure 2 is a sectional view thereof taken on line 2—2 of Figure 1;

Figure 3 is a sectional view of the keeper taken on line 3—3 of Figures 2 and 4;

Figure 4 is an inner or rear side view of the keeper, its movable member being shown adjusted inwardly from its position seen in Figure 2.

Owing to inaccuracies of construction or to relative deforming of the refrigerator body and its closure due to the expansion or contraction 35 thereof arising from the action of heat and moisture, etc., the mutually engaging portions of the latch bolt and its keeper are sometimes found to be out of that mutual registration in which the same cooperate to properly hold the closure shut.

40 It is the object of this invention to obviate this condition by providing the adjustable keeper illustrated and described herein.

In the structure illustrated by the drawing, my improved keeper or "strike" designated generally 45 1 is shown mounted as by screws 2 on the face of the jamb portion 3 of a refrigerator or the like, and a latch of any suitable type is shown mounted on the face of the closure 4 of the refrigerator's door opening as by screws 5.

50 The particular latch selected for illustration has the latch bolt 6 slidable rearwardly against the pressure of the spring 7 by drawing outwardly the arm 8 of the operating lever handle pivoted at 9 in the latch casing 10, this handle's short arm

55 11 engaging in a notch bearing 12 in the side of

the bolt. Any other suitable type of latch structure as, for instance, one having a pivotally mounted latch bolt, or a bolt movable by means other than a pivotally mounted operating handle, etc. may be employed with my improved keeper illustrated by the drawing.

This keeper comprises relatively movable members, the body member 13 on the refrigerator's jamb and the member 14 having the hook portion 15 with which the forward end 16 of the 10 latch bolt operatively engages.

The body member has an outwardly extending hollow portion or post 17 open rearwardly (toward the closure) and having spaced sides 18 provided with grooves forming slide bearings 19 extending inwardly-outwardly, i. e., toward and from the jamb. The other member 14 is movable inwardly-outwardly in the hollow body member, and has an opening 20 split at 21 to provide said member's arms 22. These arms have parallel 20 outward extensions 23 united at 24 whose lateral edges 25 slidably bear in the body member's bearings respectively.

A screw 26 journalled at 27 in the outer end of the post portion 17 and threaded in said opening 20 of member 14 may be turned to move this member to a desired adjusted position inwardly (toward the jamb) or outwardly (therefrom) and to hold said member 14 in such adjusted position.

Means are shown for holding, or holding additionally to the screw 26, the member 14 in adjusted positions. The particular means for this purpose is the conical screw 28 between, and threaded at 29 in, the arms 22 at the opposite sides of this screw. When this screw is turned inwardly these arms are pressed or sprung apart slightly, but sufficiently to cause their edges 25 to tightly bind in the body member's bearings 19 respectively and thus securely hold member 14 in the position in which it has been adjusted. A 40 bar 30 slidable in a bearing 31 in the post portion of the body member and in a registering annular groove 32 in the screw 26 holds this screw in its journal 27.

It will be seen that whenever the latch bolt 6 45 and the keeper's hook portion 15 are found to be out of such relative registration that the closure is not held in properly closed position, the keeper's member 14 may be moved to, and held in, that adjusted position which will ensure or restore the 50 desired shut position of the closure.

A resilient packing member 33 is shown between the jamb and closure for sealing the same in its closed position.

The invention being intended to be pointed out 55

in the claims, is not to be limited to or by details of construction and arrangement of the particular embodiment thereof illustrated by the drawing or hereinbefore described.

I claim:

- 5 1. A keeper for a latch bolt and the like, comprising: a body member having inwardly-outwardly extending bearings parallelly disposed; a member wherewith the latch bolt is adapted to operatively engage, movable in said bearings;
- 10 10 means in non-engaging relation with the body member, for releasably holding the movable member in adjusted moved positions in said bearings.
- 15 2. A keeper for a latch bolt and the like, comprising: a body member having an outwardly extending post portion provided with inwardly-outwardly extending bearings parallelly disposed; a member wherewith the latch bolt is adapted to operatively engage, having arms movable in said
- 20 20 bearings respectively; means in non-engaging relation with the body member, for pressing the arms into held relation with the bearings respectively to hold the second mentioned member in adjusted positions.
- 25 25 3. A keeper for a latch bolt and the like, comprising: a body member having an outwardly extending portion provided with inwardly-outwardly extending bearings parallelly disposed; a member wherewith the latch bolt is adapted to operatively engage, having arms slidable in said bearings respectively; a conical screw in non-engaging relation with the body member, between and threaded in the arms for pressing the arms apart into held relation with the bearings respectively to hold the second mentioned member in adjusted slid positions.
- 30 30 4. A keeper for a latch bolt and the like, comprising: a hollow outwardly extending body member having spaced opposite sides provided respectively with inwardly-outwardly extending bearings parallelly disposed; a member wherewith the latch bolt is adapted to operatively engage between said sides of the body member, movable inwardly-outwardly in said hollow body
- 35 35
- 40 40
- 45 45

member and having an opening split to provide a pair of arms relatively movable laterally; a screw journaled in one of said members and threaded in said opening for moving the second member into adjusted relation with the bearings; and 5 means for pressing the arms apart into held relation with the bearings respectively to additionally hold the second mentioned member in such adjusted positions.

5. A keeper for a latch bolt and the like, comprising: a hollow outwardly extending body member having spaced opposite sides provided respectively with inwardly-outwardly extending bearings parallelly disposed; a member wherewith the latch bolt is adapted to operatively engage between said sides of the body member, movable inwardly-outwardly in said hollow body member and having an opening split to provide a pair of arms relatively movable laterally; a screw journaled in one of said members and threaded 10 in said opening for moving the second member into adjusted relation with the bearings; and a conical screw between and threaded in the arms for pressing the arms apart into held relation with the bearings respectively for additionally 15 holding the second mentioned member in such adjusted positions.

6. In a latch adapted to be mounted on the door of a refrigerator or the like having a door jamb, a keeper for the latch bolt comprising: a 30 body member mounted on the door jamb having an outwardly extending portion provided with inwardly-outwardly extending bearings parallelly disposed; a member wherewith the latch bolt is adapted to operatively engage, having arms slid- 35 able in said bearings respectively; a conical screw between and threaded in the arms for pressing the arms apart into held relation with the bearings respectively to hold the second mentioned member in adjusted slid position, the screw ex- 40 tending axially toward the door in its closed position and having turning means at its end which is adjacent the door and inaccessible in said position thereof.

ALBERT F. LICKTEIG. 45
